N. KRASNER

PHONOGRAPH CABINET

Filed Nov. 8, 1921

INVENTOR
NATHAN KRASNER

BY

Morris Firestone
ATTORNEY

UNITED STATES PATENT OFFICE.

NATHAN KRASNER, OF NEW YORK, N. Y.

DESIGN FOR A PHONOGRAPH CABINET.

Application filed November 8, 1921. Serial No. 513,827. Term of patent 3½ years.

To all whom it may concern:

Be it known that I, NATHAN KRASNER, subject of the Government of Russia, residing in the city of New York, county and State of New York, have invented a new, original, and ornamental Design for a Phonograph Cabinet, of which the following is a specification, reference being had to the accompanying drawing, forming part thereof, in which the drawing is a perspective view of my new design for a phonograph cabinet.

I claim:

The ornamental design for a phonograph cabinet as shown.

NATHAN KRASNER.
